UNITED STATES PATENT OFFICE.

TIMOTHY P. CRONIN, OF ST. LOUIS, MISSOURI.

WATER HEATER.

Application filed December 29, 1924. Serial No. 758,563.

My invention relates to improvements in water heaters and has for its primary object an electrically operated water heater in which metallic electrodes are designed to be immersed in water, the water surrounding these electrodes serving the purpose of a resistance element and becoming heated by the passage of the electric current therethrough.

10 A further object is to construct an electrically operated water heater which is so arranged that the water completes the circuit by contacting with metallic electrodes and acts also as a resistance element and which 15 will automatically cease functioning as soon as the water ceases touching the electrical elements, thereby eliminating all danger of burning out the elements, causing fire, or causing dangerous explosions due to the 20 water coming in contact with a highly heated surface and suddenly flashing into steam.

In the drawings:—

Fig. 1 is an elevation of a water boiler 25 such as is used for steam or hot water heating with my device attached thereto;

Fig. 2 is an enlarged elevation of my device with the electric switch removed;

Fig. 3 is a vertical section taken on the 30 line 3—3 of Fig. 2;

Fig. 4 is a top plan view of Fig. 2;

Fig. 5 is an enlarged horizontal section taken on the line 5—5 of Fig. 3 and illustrating the manner of positioning the electrodes within the water chamber;

35 Fig. 6 is an enlarged top plan view with the upper plate removed and showing the switch whereby certain of the electrodes may be cut out of the circuit if desired;

40 Fig. 7 is an enlarged vertical section of the upper portion of one of the electrodes with the binding post formed integral;

Fig. 8 is a similar view showing a modified form wherein the binding post is molded 45 in the electrode.

In the construction of my device I employ a water container 9 which is preferably rectangular. The upper end of the container 9 is provided with a flange 10 through which a plurality of tapped holes extend, the purpose of these holes will be explained in detail later. Extending from the bottom of the container 9 is a boss 11 which is provided with internal screw threads 12 for the purpose of attaching a water connection thereto. Extending from one of the

sides and at a short distance below the flange 10 is a boss 13 which is provided with internal screw threads 14 for the attaching of a water pipe. The boss 11 is 60 the inlet port, and the boss 13 the outlet port. The water chamber 9 is provided with a coating 15, both inside and out, which coating is either porcelain or some other non-corrosive insulating substance and 65 is for the purpose of preventing any possibility of the container becoming electrified in any manner, as well as to prevent the same from becoming corroded either through the action of the water itself or through 70 electrolysis.

Resting on the flange 10 is a gasket 16 on which is placed a sheet of insulating material 17, this sheet is of the same area as the upper portion of the container 9 and 75 is secured in position by means of screws 18 which pass through certain of the screw threaded openings in the flange 10.

The plate 17 is provided with suitable spaced apart openings so as to permit the 80 binding posts 19 which project from the upper end of the electrodes 20, to pass therethrough. Against the underside of the plate 17 is placed a sheet 21 which is of resilient material and acts as a gasket to prevent leakage 85 through these holes or openings. These electrodes are secured in position on the plate by means of nuts 22 which draw the upper ends of the electrodes tightly against the packing 21. The lower ends of the electrodes extend through a plate 23 which is of insulating material and which holds the lower ends of the electrodes in spaced apart position so that there will be no danger 90 of these ends being moved to or from each other and thus vary the gap between the electrodes.

The upper edge of the plate 17 is rabbed so as to provide a shoulder on which is located a casing 24, this casing is in the 100 shape of a frame and has located on its upper edge a plate 25. The plate 25 is held in position by means of screws 26 which pass therethrough, through the plate 17 and into the remaining screw threaded openings 105 formed in the flange 10, and in order to prevent the plate from being drawn down too tight the screws 26 are surrounded by sleeves 27 which are located between the plates 17 and 25.

110 The plate 25 is provided with openings 28 through which electric conductors 29

pass, these electric conductors are secured to the binding posts of adjacent electrodes. From these electrodes, electric conductors 30 and 31 extend in a diagonal direction 5 and terminate in contact buttons 32 and 33 respectively. Located adjacent the contact button 32 is a contact button 34, and adjacent the contact button 33 is a contact button 35. Each one of the last mentioned 10 contact buttons is connected to one of the remaining electrodes by means of an electric conductor 36.

Slidably mounted on the plate 17 is a switch arm 37 which carries contact plates 38 and 39 respectively. These plates are spaced apart from each other and are of sufficient width so that the plate 38 will bridge across the contact buttons 32 and 34, and the plate 39 across the buttons 33 and 35. The purpose of this switch is to cut 20 certain of the electrodes out of the circuit and save electric current, this will be explained in detail later.

The electric conductors 29 lead to a suitable switch 40 and from this switch lead 25 electric conductors 41 which are attached to the power line. The switch 40 is of the type which is commercially known as the two 30 circuit switch, in other words, a switch which will simultaneously break the circuit in both lines so that there will be no possibility of any electric current reaching the electrodes when the switch has been turned off.

35 In Fig. 1 I have shown the switch 40 as being mounted on top of the plate 25, this, however, is not essential as the switch may be placed at any suitable point removed 40 from the device without disturbing its operation in the least. In Fig. 1 I have shown my device as attached to a heating system, either of steam or water, in which 42 is the boiler, 43 the outflow pipe, and 44 the return pipe. In attaching my device I locate a 45 valve 45 in the outflow pipe 43 adjacent the boiler, and immediately above this valve is placed a T 46; to the T is attached a nipple 47, to which nipple is attached a valve 48. To the valve 48 is attached one end of a 50 pipe 49, the opposite end of this pipe being attached to the outlet port of the water chamber 9.

To the inlet port of the water chamber is attached a pipe 50, which pipe is in turn 55 connected to a valve 51 in any suitable manner. The valve 51 being in turn attached to a T 52 which is located in the return pipe 44, and between the T 52 and the boiler 42 is attached a valve 53.

60 It is my purpose to use the device thus assembled to maintain the heating system in operation after the water has once become heated by the boiler, this is done in the following manner: The valves 48 and 51 are 65 closed and the valves 45 and 53 opened and

the contents of the boiler brought up to a suitable temperature by the use of ordinary fuel. After this temperature has been reached the valves 45 and 53 are closed and the valves 48 and 51 are opened, this permits the water which descends through the return pipe 44, due to its cooling, to enter into the bottom of the chamber 9. The electric current is then turned on and the water becomes heated by the electric current 70 passing therethrough, flows out through the pipe 49 and up through the outlet pipe 43. Should the water in the chamber 9 at any time become so hot as to be converted into steam, the action of the electric current is 75 automatically discontinued by the fact that there is not sufficient moisture in this chamber to form a circuit between the electrodes, but immediately upon condensation again forming in the chamber and becoming sufficiently deep to permit the electrodes to extend therein, electric contact is immediately 80 re-established and the heating resumed. Should I find that the water in the chamber heats too rapidly when all electrodes are 85 employed, the switch 37 is moved into the position shown in Fig. 6. This permits only two electrodes to function, the remaining being cut out of the circuit, and should it then be decided to heat the water more 90 rapidly the switch is moved into the position indicated by dotted lines so that the plates 38 and 39 will bridge across the contact buttons and throw the additional electrodes into 95 service in this manner.

100 My device can be used for maintaining a heating system to the proper temperature without any attention on the part of the user. My device can also be attached to individual radiators or heating coils and 105 operated at a relatively low cost and consumption of current and with absolutely no danger of fire, because should the water at any time evaporate completely out of the chamber 9, the flow of electric current immediately ceases because the space or gap between the electrodes is of sufficient size 110 that no arcing takes place, consequently the electrodes do not heat up but remain cold and at no time do they become any hotter 115 than the temperature of the water.

The electrodes of my device are made of metal which does not corrode from the action of water and which resists electrolysis so that a set of electrodes will last a very long time and will not discolor the water or precipitate particles of the electrodes therein which might possibly come to rest on the plate 23 and cause a short circuit.

120 My device can be used either with direct or alternating current and the consumption of current is regulated by spacing the electrodes closer together or farther apart. I have found that by bringing the electrodes closer together the current consumption is 125 130

greater and consequently the heating of the water also takes place more rapidly than if the electrodes are spaced farther apart.

While I have shown the electrodes as being square in cross section and as using four electrodes, I do not desire to limit myself to this peculiar shape and arrangement of electrodes, as these may be both varied in shape and arrangement without departing from the spirit of my invention.

In my device all of the heat is created directly in the water and consequently none lost as is the case where a resistance element is employed, because in this instance, a certain amount of electrical energy is consumed in first heating up the resistance coil, after this has been heated additional energy is employed in order to heat up the casing surrounding the heating element before any heat can be imparted to the water. This necessitates quite a consumption of electric current and these two preliminary heating elements are obviated in my device. Furthermore, where fuel is used in order to heat the water, a vast amount of heat units pass out through the chimney, then again the heat must be applied to the outside of the container in which the water to be heated is located. This consumes a great deal of heat and by heating the container in this manner a lot of heat is lost by conduction because the entire container, which is usually formed of metal, makes an excellent heat conductor. It will therefore be readily seen that by my device all these heat losses are eliminated because the heating takes place directly in the water itself and consequently permits the ready absorption of the heat units by the water without the necessity of first heating up some other element and permitting it to heat the water by conduction.

The material out of which the electrodes

is made is from such substance as platinum or other material which will not readily become oxidized so that there will always be a clean surface, which will readily permit the electrical current to pass therefrom. I have found that by using ordinary steel or iron that the surface will in time become corroded and offer resistance to the passage of the electrical current, while electrodes, which are made of carbon or similar material, will deteriorate and in time completely foul the water in which they are suspended, and thus in time build up sediment which will eventually short circuit the electrodes.

Having fully described my invention, what I claim is:

A water heater comprising a water container, open at its top, a plate of insulating material for closing said container, a plurality of electrodes carried by said plate and extending into said container, electric conductors for supplying electric energy to said electrodes, a switch mounted on said plate whereby certain of said electrodes may be placed in and out of circuit, a second plate of insulating material located above and spaced apart from the first mentioned plate, said second mentioned plate being provided with openings to permit the passage of the conductors, a switch mounted on the second mentioned plate for controlling the electric energy through said conductors, a water inlet located in the bottom of said container, a water outlet adjacent the top of said container whereby a circulation of water is obtained, and means surrounding said electrodes adjacent their lower ends for holding said electrodes in spaced relation to each other.

In testimony whereof, I have signed my name to this specification.

TIMOTHY P. CRONIN.
